UNITED STATES PATENT OFFICE.

OLOF ANDERSON, OF CHICAGO, ILLINOIS, ASSIGNOR TO WALTER P. MURPHY, OF CHICAGO, ILLINOIS.

RELEASE-RIGGING.

1,116,866.

Specification of Letters Patent. Patented Nov. 10, 1914.

Application filed August 19, 1912. Serial No. 715,787.

To all whom it may concern:

Be it known that I, OLOF ANDERSON, a citizen of the United States, residing at Chicago, in the county of Cook and State 5 of Illinois, have invented a new and useful Improvement in Release-Rigging, of which the following is a specification.

My object is to provide a release-rigging for car-couplers of a simple, strong and 10 durable construction, which will operate as a means to unlock the coupler in the event of such injury to the draft-rigging as will permit the pulling out of the draw-bar.

It happens not infrequently in the handling 15 of long and heavy trains, or in careless switching, that a part of the draft-rigging of a car will give way under excessive shock or strain and permit the draw-bar to be pulled out. The draw-bar when 20 pulled out drops to the road-bed or upon the track, whereby it is apt to become injured beyond repair, injure other parts or even derail the car.

One purpose of my invention is to over- 25 come, or at least greatly reduce, danger of the complete pulling out of a draw-bar by providing means which will operate automatically to raise the locking pin and unlock the coupler whenever the draw-bar is 30 pulled beyond a predetermined distance, whereby uncoupling will take place before the draw-bar is pulled out far enough to drop from its support.

In the accompanying drawing, I show a 35 release rigging which, except as to the particular part forming the automatic safety feature of the construction, may be regarded as of conventional form.

Referring to the drawing—Figure 1 is a 40 plan view; Fig. 2, a front elevation; and Fig. 3, a side elevation of a release-rigging constructed with my improvement.

Journalized in a common manner in brackets 45 5, on the end sill 6 of the car, is a rod or rock-shaft 7 provided at its outer end with a downwardly-extending handle 8 and at its inner end with a normally horizontally-extending crank-arm 9. The end of the crank arm 9 is bent to form 50 an inclined loop 10. Extending loosely through the loop 10 is a lever 11 terminating

in a hook 12, which engages the locking pin 13 of the coupler. The lever 11 is normally horizontal, or approximately horizontal, resting upon the part 14 of the loop and 55 bearing upward against the part 15 of the loop.

Turning of the handle 8 rocks the crank 9 and lifts the lever 11 to raise and unlock the pin 13. The lever 11 has a shifting 60 or floating connection with the loop to permit lateral movement of the draw-bar, while the train is rounding curves. The surface 14 of the loop on which the lever 11 rests is normally horizontal or substantially so 65 for a stretch sufficient to permit the draw-bar to travel to the limit of its movements under pulling and buffing strains. Any movement of the draw-bar beyond the limit provided for pulling strains will cause the 70 lever 11 to move in an upward direction upon the inclined part, or cam-surface, of the loop, thereby raising its hook-end and lifting the locking pin 13 to unlock the coupler. Thus, in the event of any injury to 75 the draft-rigging which would permit the pulling out of the draw-bar, such pulling out is prevented because when the draw-bar moves beyond a predetermined limit it is released from engagement with the coupler of 80 the adjacent car and is thereby prevented from being pulled from its support.

The foregoing description is intended to convey a clear understanding of my improvement in what I now believe to be the 85 best and simplest form of its embodiment, and no undue limitation should be understood therefrom. It is my intention to claim all that is novel in my invention and that the claim shall be construed as broadly 90 as the prior state of the art may warrant.

What I claim as new and desire to secure by Letters Patent is:—

In a release-rigging for car-couplers, the combination of a rock-shaft bent adjacent 95 to its inner end to form a crank, and having its end bent outwardly at an upward incline and thence rearwardly and inwardly to form a horizontally extending loop, the inclined initial bend of said loop forming a 100 cam surface, a laterally-swinging pin-operating lever passing over the crank and

- under the rearward bend of said loop and loosely confined therein, the said pin-operating lever being adapted to be lifted bodily by the crank when the same is raised and
- 5 thereby lift the pin into coupler-unlocking position, and the cam-portion of the loop being adapted to raise the lever and pin and unlock the coupler when the latter is moved under pulling strain beyond a predetermined distance.

OLOF ANDERSON.

In presence of—

J. G. ANDERSON,
R. A. SCHAEFER.
